UNITED STATES PATENT OFFICE.

EDWARD WESTON, OF NEWARK, NEW JERSEY.

MEANS FOR SUPPORTING SHAFTING.

No. 870,861.

Specification of Letters Patent.

Patented Nov. 12, 1907.

Application filed May 13, 1902. Serial No. 107,080½.

To all whom it may concern:

Be it known that I, EDWARD WESTON, a subject of the King of Great Britain, residing at Newark, in the county of Essex and State of New Jersey, have made 5 a new and useful Invention in Means for Supporting Shafting, of which the following is a specification.

My invention has for its objects—First, to provide novel means for supporting shaft hangers in which the shafting and counter-shafting are journaled, said means 10 being so constructed as to adapt it to be utilized with hangers of different sizes and supporting capacity and also applicable in connection with well known types of hangers now found in the market. Second, to so construct and arrange the before-mentioned means for supporting the hangers that when it becomes necessary to connect any main line of shafting with additional mechanism to be driven thereby, through the agency of additional shafting, either in alinement with any line of shafting or parallel therewith, such connection 15 20 may be effected by the attachment of hangers of the usual type, combined with my novel means, by any person, thereby avoiding the necessity of employing on such occasions, the services of a mill-wright or other similar expert.

25 For a full and clear understanding of my invention such as will enable others skilled in the art to construct and use the same, reference is had to the following specification and accompanying drawings, in which,

Figure 1 is an enlarged side elevational view of one 30 of my hangers secured by my novel form of separable clamp to my novel arrangement of tubular string pieces, one part of the clamp being broken away and illustrated with the string pieces in sectional view in such manner as to show the inter-connecting clamping bolts 35 in elevational view. Fig. 2 is a top plan view of the lower half of my novel form of separable clamp; and Fig. 3 is a top plan view of the upper half thereof, the bolts which unite the two together and the hanger not being shown in these views. Fig. 4 is a sectional view 40 of the separable clamp taken on the line $x-x$ Fig. 1 and as seen looking thereat from right to left in the direction of the arrows. Fig. 5 is a sectional view taken through a pair of tubular string pieces, illustrating in side elevational view a modified form of separable 45 clamp adapted to be used directly beneath the lower member of a truss or cross-beam which supports the ceiling or roof of a building. Fig. 6 is a top plan view of the modified form of clamp illustrated in Fig. 5 and as seen looking thereat from the top toward the 50 bottom of the drawings, short portions of the supporting string-pieces being also shown in plan view. Fig. 7 is a bottom plan view of the same part as seen looking at Fig. 5 from the bottom toward the top of the drawing. Fig. 8 is a sectional view taken through the lower

member of a roof truss or cross-beam composed of two 55 angle irons, illustrating also in elevational view the manner of supporting the string-pieces by the separable clamp shown in Figs. 5 and 6 from points directly beneath the lower surface of such a member or beam.

Prior to my invention it has been customary to support lines of shafting for driving machinery in factories and kindred places, by securing to the joists or to the lower members of the roof trusses in various ways one or more lines of wooden string pieces, the arrangement being such that the hangers which support the shafting are secured thereto by bolts, it being necessary that a mill-wright or other expert in the alinement of shafting be employed to secure the same in the manner indicated, in order that it may be located in proper alinement and so as to obtain the best mechanical results. 60 65 Such an arrangement also necessitates always the employment of a mill-wright or similar expert when it becomes necessary to add additional machinery driven either by parallel lines of shafting or by lines of counter shafting; or shafting in alinement with that already 70 75 in use.

My invention contemplates a means of suspension for the main line shafting and secondary and counter shafting of a power system, such that these objectionable features are entirely overcome and that the system 80 is so flexible in its nature as to make it possible to utilize practically any part of the floor space, when desired; or, to vary the conditions of the application of power from the main line of shafting to suit the demands which may be made.

In Figs. 1 to 4 inclusive I have illustrated my novel means for adjustably securing the string pieces which support additional shafting in lines parallel with the main line shafting, and for making said string pieces an available means of support for various sizes of hangers 90 found in the open market. T^1 , T^1 represent the string pieces which are made preferably of tubular steel, although they may be of solid metal accurately turned. o , o^1 are the two parts of a separable clamp adapted to grip or clamp the before-mentioned string pieces between their opposite ends, as shown in Fig. 1. Bolt holes are provided at the opposite ends of this separable clamp for the purpose of receiving bolts I^2 , I^2 . w , w , are longitudinal slots in the opposite ends of the lower halves o^1 of the separable clamps, their function being 100 to adapt the clamp for use with hangers H^1 of different size or carrying capacity, such hangers being of well known construction and on sale in the market. The hangers H^1 are secured to the lower halves of the separable clamps by bolts I^3 , I^3 extending through the ob- 105 long slots w , w , in the opposite ends thereof.

In Figs. 5 to 8 inclusive I have illustrated a clamp by which the string pieces T^1 , T^1 are secured directly to the

lower members T of the roof-trusses or the cross-beams of the ceiling of the building. This clamp is composed of two parts o², o³ having bolt-holes in their opposite ends and semi-cylindrical clamping parts B'' adapted 5 to grip or secure the string-pieces T¹, T¹ directly to the lower member of the roof-trusses or members.

- In Fig. 8 I have illustrated in an enlarged view the manner of securing these string-pieces directly beneath the lower member of a truss by bolts I² and a shouldered 10 washer U which is adapted to be located between the two angle irons of the lower member of the truss and act as a bearing for the nut on the bolt I², the entire arrangement being such, as is obvious, that the clamps may be adjustable to the right or left as seen looking at Fig. 4 in 15 either direction so as to effect the proper alignment of the counter-shafting and parallelism thereof with the main lines of shafting.

In view of the above description it will be apparent on inspection of the drawings that, by reason of the adjustability of the several types of separable clamp, 20 hangers and other attachments hereinbefore described and of the manner of supporting the shafting and the counter-shafts, it will be possible to make adjustments to suit all conditions which may arise with relation to 25 machinery upon the work-benches, or upon the floor in any part of a room which is supplied with counter-shafts supported and arranged as hereinbefore described and illustrated in the accompanying drawings, and this feature of flexibility and adjustability of the 30 system as a whole constitutes one essential element of my invention.

I am aware that it is not broadly new with me to support lines of shafting and parallel lines of counter-shafting directly from the ceiling or roof I-beams of a building 35 by parallel stringers adjustably secured above the lower flanges of said beams by bolts and clamping strips adapted to clamp the opposite ends of said stringers in position, and that it is old in the art to support lines of counter-shafting upon V-shaped stringers permanently 40 secured by angle irons directly to the cross-beams in the ceiling of a building; and I make no claim hereinafter broad enough to include such structural devices.

Having thus described my invention what I claim and desire to secure by Letters Patent of the United 45 States is:—

1. Means for supporting string pieces in a factory building, embracing a two-part clamp provided with means for

holding said parts together and securing the string pieces between them; in combination with additional means for securing the clamp directly to one of the lower members of 50 the roof-trusses, substantially as described.

2. Means for supporting hangers of different size in a factory building from parallel string pieces, embracing a two-part clamp provided with means at its opposite ends for clamping the hanger to the string-pieces, the lower half 55 of said clamp being provided with oblong slots adapted to secure the heads of bolts when affixed to such hanger, substantially as described.

3. Means for supporting shafting from the lower members of the roof-trusses of a factory building, embracing 60 two-part clamps provided with semi-cylindrical clamping parts, bolts, and nuts adapted to support parallel string pieces beneath said trusses; in combination with pairs of two-part separable clamps adapted in turn to grip or clamp the before-mentioned string pieces, the lower halves of the 65 latter clamps being provided with oblong slots; together with hangers having bolts extending through the before-mentioned slots and adapted to secure them adjustably therein, substantially as described.

4. Means for supporting shafting in a building, embracing 70 pairs of string pieces; means for adjustably supporting said string-pieces in pairs beneath the lower members of the roof-trusses of the building; additional means adjustably secured to said string-pieces in pairs for supporting shaft hangers, the arrangement being such that any 75 line of supported shafting may be adjusted both longitudinally and laterally with relation to the floor space of the building, substantially as described.

5. Means for supporting shafting in a building, embracing 80 parallel lines of string pieces and means for adjustably securing the opposite ends of said string-pieces to the lower members of the roof-trusses; in combination with detachable and adjustable clamps secured in pairs to the stringers, and hangers supported by said clamps, the arrangement being such that any line of supported shafting 85 may be adjusted both longitudinally and laterally with relation to the floor space of the building, substantially as described.

6. Means for supporting shafting in a building, embracing 90 parallel lines of string pieces and means for adjustably securing said string pieces to the lower members of the roof-trusses; in combination with clamps secured in pairs to the stringers, said clamps being adjustable thereon and so constructed as to support different sized hangers, the entire arrangement being such that any line of shafting 95 may be adjusted both longitudinally and laterally with relation to the floor space of the building and different sized hangers may be adopted at the will of the user, substantially as described.

In testimony whereof I have signed my name to this 100 specification in the presence of two subscribing witnesses.

EDWARD WESTON.
